UNITED STATES PATENT OFFICE

FRANZ HOCHMAYR, OF VIENNA, AUSTRIA, ASSIGNOR OF ONE-HALF TO KARL WEINTOGL, OF VIENNA, AUSTRIA

MASSAGE APPARATUS

Application filed February 25, 1930. Serial No. 431,260, and in Germany December 27, 1929.

This invention relates to an improved massage apparatus operated by fluid pressure.

Two types of massage apparatus of this kind are known. According to one of these known constructions vibratory and pulsatory massage of the part of the body to be treated is effected directly by a diaphragm, while with the apparatus of the other type the diaphragm actuates an applicator or beater.

Compared with these known types, the massage apparatus according to the present invention possesses the advantage that it can be used for both kinds of massage above referred to and further cools the part of the body treated at the time by means of the pressure fluid which operates the diaphragm or beater. A further advantage of the apparatus according to the present invention resides in a very advantageous mode of supplying and discharging the pressure fluid.

In carrying out the present invention the diaphragm is arranged in such a manner that it acts either directly as massage-member or as means communicating vibratory or pulsatory movement to a beater acting as massage-member.

One mode of carrying out the present invention is illustrated by way of example on the accompanying sheet of drawings in which:—

Fig. 1 is a part-sectional view of the massage apparatus with the diaphragm as massage-member.

Fig. 2 is a sectional view of the forward end of the massage apparatus with beater-holder operated by a diaphragm and means for cooling the part of the body treated at the time.

A pipe 2 is arranged in a pipe 1, serving as handle, in such a manner, that a space 1' remains between the inner wall of the outer pipe 1 and the outer surface of the inner pipe 2 for the supply of pressure fluid, for instance water under pressure, to the diaphragm 3. The pressure fluid returns from the diaphragm by way of the inner pipe 2. The forward end of the two pipes are joined together so as to form a partly spherical member bridging the space between the two

pipes. However the forward end of the inner pipe 2 is not closed. Holes 19 are provided in the said bridging member or connecting wall. If the diaphragm 3 is applied to the partly spherical end of the pipes 1 and 2, the fluid forced through the holes 19 will lift the diaphragm and thereafter enter the inner pipe 2 and thus vibrate or pulsate the diaphragm. In order that the diaphragm directly acts as massage-member, the same is provided with suitably shaped extensions or applicator 3' of rubber or the like (shown in dotted lines in Fig. 1). The diaphragm 3 is secured to the forward end of the pipes in the following manner:—

A nut 14 is screwed to the screw-threaded forward end of the outer pipe 1 and provided with a circular groove for the reception of the diaphragm 3. Before tightening the nut 14, the diaphragm is stretched over the forward end of the pipe-assembly and fixed in the groove of the nut by a clamping ring 15. In view of this arrangement, the diaphragm 3 with its applicator 3' can be readily removed and a diaphragm with an applicator of other shape can be readily secured to the apparatus.

The device, shown on an enlarged scale in Fig. 2, is secured to the nut 14, if it is desired to use a separate beater, which is operated by the diaphragm, and to cool the part of the body which is treated, e. g. massaged at the time.

For this object the nut 14 is externally screw-threaded and a cap 17 is screwed thereto. This cap serves for guiding the holder 16 of the beater (not illustrated) and is provided with means for attaching a hood 18 of rubber or the like, which encloses the beater and is charged with cooling water. A spring, for withdrawing the beater-holder 16, is placed around the latter and one end of this spring rests on a disc, bearing on the diaphragm 3, while the other end of said spring rests on the shoulder of the stepped bore of the cap 17. In view of this arrangement the vibrations or pulsations of the diaphragm 3 are transmitted to the reciprocating beater-holder 16. The beater or massage-member is screwed to or otherwise secured to the outer end of said holder 16. A rubber-tube

20 establishes communication between the pressure-fluid chamber 1' and the interior of the hood 18, while a rubber-tube 21 connects the latter with the inner pipe 2. During 5 the operation a part of the pressure-fluid, which is supplied to the diaphragm 3, enters by way of the tube 20 the hood 18; cools the part of the body under treatment and is discharged by way of the tube 21 into the inner 10 pipe 2, through which it leaves the apparatus together with the fluid coming from the diaphragm.

The beater or massage-member operates in 15 the fluid flowing through the hood 18 and, in view of the combined massage- and cooling effect, this arrangement is particularly adapted for heart-massage. Cold or hot water can be used as pressure fluid, so that 20 the apparatus can be used for different kinds of treatment.

The branches of the pipes 1 and 2 for the attachment of the tubes 20 and 21 are closed by screw-plugs 22 or in other convenient manner, if it is desired to use the apparatus 25 without hood 18 or without beater, e. g. in the way shown in Fig. 1.

The pipes 1 and 2 are connected for instance to the city water mains in the following manner:—

30 A screw-cap 10 is screwed to the rear end of the outer pipe 1 and connects a flexible pipe or hose 9 to the latter. Tubes 7 and 8 for supplying and leading of the pressure-water are arranged within the hose 9. The 35 tubes 7 and 8 are in communication with the chamber 1' and the inner tube 2 respectively by means of connecting members 5 and 6, secured in corresponding holes in the bottom 4 of the pipes 1 and 2.

40 The other end of the hose 9 is secured to a fitting, adapted to be attached to the water-tap. The fitting comprises a head-piece 11 with a rubber-insertion 13 for attachment to the water-tap and a discharge member 12 through which the water passes into the sink. The head-piece 11 is in communication with the supply tube 7, while the end of the discharge tube 8 passes into the flared end 12.

I claim:

50 1. Massage apparatus operated by pressure fluid comprising in combination two pipes arranged one within the other, the space between both pipes serving for the supply of the pressure fluid while the inner pipe constitutes the fluid-discharge passage, a wall 55 bridging said space at the forward end of said pipes, perforations in said bridging wall, a diaphragm covering the forward end of said pipes and resting on said bridging wall, a nut screwed to the forward end of the pipes, means securing the diaphragm to said nut, a screw-cap with a centrally disposed bore secured to said nut, a beater-shaft passing through said bore and resting on said diaphragm, a cup-shaped member secured to said

screw-cap, and means permitting the circulation of the pressure fluid through said cup-shaped member for cooling the part of the body treated at the time.

2. Massage apparatus operated by pressure fluid comprising in combination two pipes arranged one within the other, the space between both pipes serving for the supply of the pressure fluid while the inner pipe constitutes the fluid-discharge passage, a wall 75 bridging said space at the forward end of said pipes, perforations in said bridging wall, a diaphragm covering the forward end of said pipes and resting on said bridging wall, a nut screwed to the forward end of the pipes, 80 means securing the diaphragm to said nut, a screw-cap with a centrally disposed bore secured to said nut, a beater-shaft passing through said bore and resting on said diaphragm, a hood of an elastic material secured to said screw-cap, and means establishing communication between the interior of said hood and the pressure-fluid space between the two pipes as well as between the interior of 85 the hood and the inner pipe to cause circulation of the pressure-fluid through the hood.

In testimony whereof I affix my signature.

FRANZ HOCHMAYR.
